Attorney.

UNITED STATES PATENT OFFICE.

CARL PETERSON, OF NEWCASTLE, INDIANA.

LID ADJUSTER AND SUPPORT.

1,405,433.

Specification of Letters Patent. Patented Feb. 7, 1922.

Application filed December 10, 1921. Serial No. 521,279.

To all whom it may concern:

Be it known that I, CARL PETERSON, a citizen of the United States, residing at Newcastle, in the county of Henry and State of Indiana, have invented new and useful Improvements in Lid Adjusters and Supports, of which the following is a specification.

This invention relates to improvements in means for holding the hinged lids of pianos, piano benches, and receptacles of all kinds, at different heights, and the object is to provide a device that will automatically lock itself by the raising of the lid, and to provide a lock which can be released and returned to a closed position by raising the lid to a still higher position.

I accomplish the above and other objects which will hereinafter appear, by the means illustrated in the accompanying drawing, in which—

Fig. 1, is a view in side elevation of my invention removed from a lid and receptacle. Fig. 2, is an edge view of the same. Fig. 25 3, is a longitudinal vertical section of a piano bench with the lid raised by means of my invention placed near the outer or free end of the lid, and Fig. 4 is a fragment of a piano case with the lid raised by my 30 invention located near the hinge edge of the lid.

Like characters of reference indicate like parts in the several views of the drawing.

My invention comprises a plate 3 with 35 screw holes by which it is secured by screws to a lid 6, secured by hinges 4 to a receptacle 5. Depending from the plate is an integral ear 7 to which a flattened portion of a hook-bar 8 is pivoted. A leaf-spring 40 9 is attached at one end to the plate 5 and bears, near its outer free portion, against the end of the hook-bar 8. The end of the bar 8 is flattened in a plane to contact with the spring and hold the bar-proper by the 45 spring pressure, in contact with the notched edge of a locking-plate 10. The free lower end of the hook-bar is bent laterally in the manner shown in Fig. 2 to form a hook 11.

The locking-pin 10 is oval in general 50 form, with more or less pointed ends to facilitate the shifting from one edge to the other, of the hook 11, and on that edge of the plate which is toward the hinge of the lid a series of notches 12 is provided. 55 These notches are here shown as three in

number but they may be more or less than that depending upon the number of positions at which it is desired to lock the raised lid. The plate 10 is secured to the side of the receptacle 5 in the path of the hook 11, 60 as shown in the drawing, and it may be held away from the supporting surface of the box by bosses 13 to secure greater freedom of action of the hook.

The above described device may be located at any desired distance away from the hinge of the lid. For piano benches, where it is often desirable to vary the height of the seat to suit the convenience of the player, it is best to place the holding device near the hinge where it will be less in evidence and afford a higher range of movement for 70 the lid, as shown in Fig. 4.

The operation is the same for all locations of the lid holding device. The shape of the end of the hook-bar near its pivot is such that when pressed by the spring 9 80 the bar stands relative to the locking plate 10 when the lid is closed as shown in the lower dotted lines in Fig. 3, where, as the lid is raised the hook 11 will follow the notched side of the plate 10 and enter the 85 notches 12 in the regular order by the action of the spring. The entrance to the notches slope upwardly to hold the hook against a downward movement, but to allow the hook to raise out of a notch by an upward movement of the lid. Consequently, the lid may be raised until a holding notch at the required height is reached. Then, when it is desired to close the lid, it is raised until the hook has passed the upper 90 end of the locking-plate, and thereupon the spring will move the hook to the other side of the locking-plate in the then elevated position of the hook and by lowering the lid the hook will be returned to the place of 95 beginning.

Should a notch too high be entered by the hook the adjustment of the lid can be made over again by first lifting it above the end of the locking-plate and closing the lid and 100 by then raising it to the height desired.

Having thus fully described my invention what I claim as new and wish to secure by Letters Patent of the United States, is—

1. The combination of a receptacle having 110

walls, and a lid hinged to one of the receptacle walls, of a lid-adjuster and support comprising a bar pivotally secured to the lid and terminating at its free end with a hook, spring means for holding the bar at a normal position, and a locking-plate secured to a wall of the receptacle, said plate having notches into which the hook on the bar is pressed by the spring upon 10 raising the lid.

2. The combination of a receptacle having walls, and a lid hinged to one of the walls, of a lid-adjuster and support comprising a bar pivoted to the lid and terminating at 15 its free end with a hook, spring means for yieldingly holding the bar at a normal position, and a locking-plate secured to a wall of the receptacle, said plate having upper and lower tapering ends and downwardly 20 oblique notches in one edge to successively engage the hook by the action of the spring which presses the hook against the notched edge of the plate as the lid is raised and which causes the hook to pass down along

the other edge of the plate as the lid is 25 closed.

3. The combination of a receptacle having rigid walls and a lid hinged to one of the walls, of a lid-adjuster and support comprising a plate secured to the lid and having 30 an ear, a bar having a flat end pivoted to the ear with a hook at its opposite free end, a leaf-spring on the plate pressing the adjacent flat end of the bar to hold the bar in a yieldingly normal depending position, 35 and a locking-plate generally oval in shape secured to a wall of the receptacle with one of its small ends toward the lid, said plate having downwardly oblique notches in one edge to successively engage the hook 40 by the action of the spring, said spring pressing the hook against the notched edge of the plate as the lid is raised and against the opposite edge of the plate as the lid is closed. 45

Signed at Newcastle, Indiana, this the 3rd day of December, 1921.

CARL PETERSON.
